UNITED STATES PATENT OFFICE.

JOSEPH EIFEL, OF CHICAGO, ILLINOIS.

WRENCH.

1,181,653.

Specification of Letters Patent. Patented May 2, 1916.

Application filed June 26, 1912. Serial No. 706,078.

To all whom it may concern:

Be it known that I, JOSEPH EIFEL, a citizen of the United States, and a resident of Chicago, in the State of Illinois, have invented certain new and useful Improvements in Wrenches, of which the following is a specification.

My present invention relates to wrenches in general and more particularly to wrenches having variable jaw openings, and has special reference to the provision of an improved wrench embodying the most valuable features of wrenches of a number of different types known to me, and avoiding the defects thereof.

The principal objects of my present invention are the provision of a wrench having jaws one of which may be rapidly moved relatively to the other; a wrench thus characterized which will not tend to work open in handling, thus requiring repeated settings or adjustments during a single operation; one which will have small crushing effect tending to abrade, flatten or otherwise disfigure articles upon which it is used; the provision of an improved plier form wrench adapted for wide separation of the jaws without concurrent wide opening of the handles; and one wherein relatively slight manipulation is required either in moving the article acted upon or in obtaining a fresh hold thereupon; the provision of a wrench wherein the parallelism of the jaws may be readily maintained irrespective of the size of the object operated upon; the provision of a wrench wherein the number of contact points of the jaws thereof with the article operated upon may be increased and generally to provide an improved and more efficient type of wrench than is at this time available, together with such further and additional objects as may hereinafter appear.

Wrenches of different types in use at this day as known to me are largely objectionable in the following respects: Wrenches having fixed jaws such as the S and the "alligator" types are disadvantageous in use in that a large number of different sizes is required for work upon the many different sizes of nuts in common use with consequent expense and inconvenience in selecting one of suitable size, and moreover, seldom exactly fit

any nut and have a tendency to turn or mar the corners or crush or otherwise disfigure the finish as when nickel plating or japan coating is used. The adjustable wrenches, pliers and tongs are slow in operation, do not grip and hold the nut rods, or pipes promptly and efficiently and tend to work open in operation, making it necessary to repeatedly adjust them to the work; with the exception of a few wrenches of the ratchet type which have but limited application and but narrow range of utility, all wrenches known to me require to be withdrawn from the work and a new grip found after moving the work a small distance. Pipe wrenches generally, including the "Stillson" type, can be adjusted but slowly and inasmuch as their engagement with the pipe is effected by a cutting in of their gripping surfaces they tend to mar the finish and to flatten or crush the pipe, especially pipe of light weight; the plier types of wrenches are used at a disadvantage in that when the jaws are widely separated the handles are simultaneously widely separated rendering them awkward in use and difficult to effectively grasp. Other disadvantages of the wrenches available at this day are known to those who are skilled in the art and need not be further dwelt upon.

In overcoming the stated and other objections and disadvantages, and in gaining the objects above mentioned, as well as certain further benefits and advantages to be below pointed out, I have provided the constructions illustrated in the accompanying drawings, wherein—

Figure 1 is a side elevational view illustrative of an embodiment of my present invention in the form of a monkey wrench; Fig. 2 is a plan view of the wrench of Fig. 1; Fig. 3 is a longitudinal sectional view taken on the line III—III of Fig. 2; Fig. 4 is a transverse sectional view taken on the line IV of Fig. 1; and Figs. 5 and 6 are elevational views of modified forms of jaws adaptable for use with the wrench of Fig. 1.

Referring first more particularly to Figs. 1 to 4, it will be seen that for purposes of illustration I have here shown a wrench embodying my improvements, which is useful

for the purposes for which the ordinary monkey wrench is commonly used, but is adapted to serve such purposes in a better manner. On inspection of Fig. 1 more particularly it will be observed that I provide a shank 10 having at one end a handle 11 and at the other end a jaw 12. The shank 10 is grooved as indicated at 13 to receive the shank 14 of the opposing jaw 15 which is slidably mounted therein and provided with ratchet teeth as indicated at 16. For holding the jaws 12 and 15 in predetermined position I employ a bifurcated lever 17, pivoted to the shank 10, as indicated at 18, and engaging by means of a pin 19 the slot 20 in a sliding block 21 provided with ratchet teeth as indicated at 22, adapted to engage with the ratchet teeth 16. For normally holding the members 14 and 21 in contact, and in engagement by means of the teeth 16 and 22, I employ a sliding yoke 23 slotted on each side, as at 24 and 25, for engagement with the projecting ends of the pins 26 and 27, 27' respectively carried by the shank 19 and the block 21. To hold the yoke 23 in adjusted position I provide thereon a spring 28 provided with a projecting portion 38^a adapted to engage notches 30 formed in the shank 10 and in providing means for holding the 30 toothed portion 22 of the block 21 in engagement with the toothed portion 16 of the shank 14 I employ a spring 31 riveted to the yoke 23 at 32 and having a downward projection 34 passing through an aperture 35 in such yoke and bearing upon the face 36 of such sliding block 21. For locking the members 11 and 17 in position and thus temporarily forming a single operating handle I provide a toothed pawl 37 pivoted in the 40 shank 10 as indicated at 38 and adapted to engage a toothed portion 39 of the handle 17, a spring 40 being provided for sustaining the pawl in position ready for engagement. To prevent the shank 14 from sliding too 45 freely relatively to the shank 10 I cut away the said shank 14, as indicated at 41, and insert therein a spring 42 bearing on the bottom 43 of the said shank 10. In the operation of the wrench above described it will be 50 understood that when the yoke 23 is moved outward as far as the slots 25 will permit, the pins 27 and 27' hold it in the depressed position shown so as to prevent the toothed faces 16 and 22 from disengagement 55 and thereby the jaws 12 and 15 from relative longitudinal movement. Likewise that when the yoke is moved inwardly a short distance the pins 27, 27' will force it upward sufficiently to allow the teeth 16 and 22 to 60 pass each other, but the spring 31 will continue to press upon the face 36 of the block 21 sufficiently to maintain engagement and prevent movement of such block to inward, though permitting the movement thereof 65 outward since the ratchet teeth 22 tend to

slide over the teeth 16. Furthermore that when the yoke 23 is moved farthest inward, the block 21 is raised sufficiently to entirely disengage the teeth 16 and 22, and permit movement of the block 21 in either direction. 70 Similarly that by virtue of the extension 38^a of the spring 28, striking the pawl 37, such pawl is thrown out of engagement with the toothed portion 39 of the lever 17. From the foregoing description it will be observed 75 that in the use of a wrench embodying my invention in the form above described, the yoke 23 is drawn farthest inward, allowing the ready disengagement of the members 21 and 14, and thus relative movement of the 80 jaws 12 and 15 which are then set at as close as possible an approximation of the correct distance apart, the handles being then first arranged in a convenient position for operation, and afterward slightly opened. The 85 yoke 23 is thereupon moved outward and the handles 11 and 44 of the shank 10 and the lever 17 are brought together as far as may be necessary to hold the nut or other object engaged. It will likewise be observed that 90 inasmuch as the pivot pin 18 is fixed and the pivot 19 movable to the left in the approximation of the handles 11 and 44, thus moving the jaw 15 toward the jaw 12, any pressure tending to draw the handles together is 95 proportionately transmitted to the jaw 15 and thus that the greater the pressure exerted upon the handle 44 in the operation of the device, the greater the pressure exerted upon the nut or other object engaged. 100 Moreover, when the yoke 23 is in the position shown mere separation of the handles 11 and 44 opens the jaws sufficiently to change the hold, or if desired, gain a hold at a different angle, without removing the 105 jaws from the work. In working on irregularly shaped objects by moving the sleeve until the pins occupy positions relatively to the slots indicated at 26' and 27' the jaws may be opened wider by virtue of the 110 ratchet action between the teeth 16 and 22 above explained. As is clearly to be seen on reference to Fig. 1, by virtue of the disposition of cutting edges 45 and 46 on the jaws 12 and 15 the device above described 115 may be readily used as a wire cutter.

Referring now more particularly to the device of Fig. 5, on inspection of this figure it will be noted that by providing jaws 12 and 15^a having suitable curved and toothed 120 engaging surfaces, as indicated at 47, 48 and 49 and 50, respectively, the surfaces 47 and 48 being in juxtaposition but of different radii, in the wrench construction above described an improved pipe wrench is provided, which is advantageous in that it may be opened, quickly arranged about the pipe, adjusted and quickly applied thereto, by simple manipulation of the handle 44, and as quickly removed, and that by virtue of 125

the improved arrangement of teeth shown, a four point hold may be readily obtained and thus any tendency toward flattening or crushing the pipe largely avoided, and moreover that, owing to the utilization of the actuating lever arrangement described, it is possible to vary the pressure on the pipe proportionately to the force required to turn it and independently of the friction of the jaws on the pipe. Inasmuch as in tightening nuts and bolts, as well as in pipe fitting, as a rule no very great amount of pressure is required until the object acted upon has been moved nearly to a seat, a wrench which is so readily adjustable and so quickly permits the obtainment of a new hold, and likewise with equal facility allows the application of great final pressure for the last of the movement, presents obvious advantages.

Referring now more particularly to Fig. 6 it will be apparent that I have here also shown a form of jaws applicable to wrenches of the type disclosed in Fig. 1. The present form of jaws, as well as those of Fig. 1 being provided with cut out portions 51, 52 whereby four points or more of application to the nut or other object gripped may be attained, which construction is useful in acting upon nuts of contours other than the standard square and hexagon forms, and especially those having non-parallel sides. Obviously when jaws of the type used in Fig. 6 are employed, relative opening of the jaws 12° and 15° upon movement of the handle 44 away from the handle 11 will be greater than when jaws arranged such as the jaws 12 and 15 are employed.

From the foregoing description of the construction and operation of the several embodiments of my invention it will be observed that all of the several types disclosed are provided with means whereby the jaws may be instantly opened and closed to a limited extent, for shifting relatively to the work, thereby making it feasible to utilize notches such as 50—51 for the purpose of engaging the corners, as well as flat faces of nuts, giving a much firmer hold thereupon. It will thus be observed that by the use of the several embodiments of my invention illustrated I am able where it is desirable to engage a nut on parallel faces, on opposed corners, or on a corner opposed to a face, with more holds and thus with a finger engagement than is possible with any form of a wrench known to me. Since the pressure applied upon closing the wrench may be very readily varied, it is obvious that the pressure applied to any nut, pipe or other object worked upon may be gaged to suit conditions with the greatest of facility. Other advantages of my present invention will be apparent to those who are skilled in the art to which it pertains.

Having thus described my invention and

illustrated its use, what I claim as new and desire to secure by Letters Patent is:

1. A device of the character described comprising, in combination, a pair of co-operating relatively slidable jaws, a pivoted lever for moving one of said jaws relative to the other jaw, a block, a member connected to said movable jaw, said block and member being provided with means for engaging each other, and said lever having a pivotal engagement with said block, the pivot point being located between the jaws and the block, and means independent of said pivoted lever for holding said block in engagement with said member irrespective of the position of the said lever.

2. A device of the character described comprising, in combination, a pair of co-operating relatively slidable jaws, a pivoted lever for moving one of said jaws relative to the other jaw, a block, a member connected to said movable jaw, said block and member being provided with means for engaging each other, and said lever having a pivotal engagement with said block, the pivot point being between the jaws and said engaging means, and means independent of said pivoted lever for releasably holding said block in engagement with said member irrespective of the position of the said lever.

3. A device of the character described comprising, in combination, a pair of co-operating relatively slidable jaws, a pivoted lever for moving one of said jaws relative to the other jaw, a block, a member connected to said movable jaw, said block and member being provided with means for engaging each other, and said lever having a pivotal engagement with said block, the pivot of the said lever and the pivotal connection between the said lever and the block being both located between the jaws and said engaging means, and means independent of said pivoted lever for holding said block in engagement with said member irrespective of the position of the said lever.

4. A device of the character described comprising, in combination, an operating lever provided with a jaw, a second lever pivotally engaging said first lever, a member provided with a second jaw slidably mounted relatively to said first jaw and having a portion provided with ratchet teeth, and a block pivotally engaging said second lever and provided with ratchet teeth engaging said first mentioned teeth, said first mentioned jaw being disposed between said last mentioned jaw and said block, and means independent of said pivoted lever for holding said block in engagement with said member irrespective of the position of the said lever.

5. A device of the character described comprising, in combination, an operating lever provided with a jaw, a second lever

- 5 pivotally engaging said first lever, a member provided with a second jaw slidably mounted relatively to said first jaw and having a portion provided with ratchet teeth, and a block pivotally engaging said second lever and provided with ratchet teeth engaging said first mentioned teeth, the toothed portion of said member attached to said slideable jaw being mounted in first mentioned lever and between it and said block, and means independent of said pivoted lever for holding said block in engagement with said member irrespective of the position of the said lever.
- 10 6. A device of the character described comprising, in combination, an operating lever provided with a jaw, a second lever pivotally engaging said first lever, a member provided with a second jaw slidably mounted relatively to said first jaw and having a portion provided with teeth, a block pivotally engaging said second lever and provided with teeth engaging said first mentioned teeth, and a sliding yoke engaging said first mentioned lever and bearing on said block for retaining said block in position.
- 15 7. A device of the character described comprising, in combination, an operating lever provided with a jaw, a second lever pivotally engaging said first lever, a member provided with a second jaw slidably mounted relatively to said first jaw and having a portion provided with ratchet teeth, a block pivotally engaging said second lever and provided with ratchet teeth engaging said first mentioned teeth, and a sliding yoke engaging said first mentioned lever and bearing on said block for retaining said block in position.
- 20 8. A device of the character described comprising, in combination an operating lever provided with a jaw, a second lever pivotally engaging said first lever, a member provided with a second jaw slidably mounted relatively to said first jaw and having a portion provided with ratchet teeth, a block pivotally engaging said second lever and provided with ratchet teeth engaging said first mentioned teeth, and a yoke engaging said first mentioned lever and bearing on said block for retaining said block in position, said yoke being provided with yieldingly resistant means for normally maintaining it in position against movement relatively to the lever.
- 25 9. A device of the character described comprising, in combination an operating lever provided with a jaw, a second lever pivotally engaging said first lever, a member provided with a second jaw slidably mounted relatively to said first jaw and having a portion provided with ratchet teeth, a block pivotally engaging said second lever and provided with ratchet teeth engaging said first mentioned teeth, and a yoke engaging said first mentioned lever and bearing on said block for retaining said block in position, said yoke being provided with ratchet teeth, a block pivotally engaging said second lever and provided with ratchet teeth engaging said first mentioned teeth, and a yoke having pin and slot engagement with said first mentioned lever and said block adapted for alternately holding said block in engagement with said member and for lifting said block out of engagement with said member.
- 30 10. A device of the character described comprising in combination an operating lever provided with a jaw and a notch, a second lever pivotally engaging said first lever, a member provided with a second jaw slidably mounted relatively to said first jaw and having a portion provided with ratchet teeth, a block pivotally engaging said second lever and provided with ratchet teeth engaging said first mentioned teeth, and a yoke engaging said first mentioned lever and bearing on said block for retaining said block in position, said yoke being provided with a spring having a projection for engaging the notch on said first mentioned lever for normally maintaining the yoke in position against movement relatively to the lever.
- 35 11. A device of the character described comprising, in combination an operating lever provided with a jaw, a second lever pivotally engaging said first lever, a member provided with a second jaw, such member being slidably mounted relatively to said first jaw and having a portion provided with ratchet teeth, a block pivotally engaging said second lever and provided with ratchet teeth engaging said first mentioned teeth, and a yoke engaging said first mentioned lever and bearing on said block for retaining said block in position, said levers being provided with means for locking them in position and said yoke being provided with means for opening said locking means upon movement of the yoke.
- 40 12. A device of the character described comprising, in combination, a pair of co-operating relatively slideable jaws, a pivoted lever for moving one of said jaws relative to the other jaw, movable means for releasably holding said movable jaw in position, and means for locking said lever in position, said movable holding means being mounted for opening said locking means upon releasing said jaw.
- 45 13. A device of the character described comprising, in combination, a pair of co-operating relatively slideable jaws, a pivoted lever for moving one of said jaws relative to the other jaw, movable means for releasably holding said movable jaw in position, and a pawl and ratchet for locking said lever in position, said movable holding means being mounted for tripping said pawl upon releasing said jaw.
- 50 14. A device of the character described comprising, in combination, a pair of co-operating relatively slideable jaws, a pivoted lever for moving one of said jaws relative to the other jaw, movable means for releasably holding said movable jaw in position, and a pawl and ratchet for locking said lever in position, said movable holding means being mounted for tripping said pawl upon releasing said jaw.
- 55 15. A device of the character described comprising, in combination, a pair of co-operating relatively slideable jaws, a pivoted lever for moving one of said jaws relative to the other jaw, movable means for releasably holding said movable jaw in position, and a pawl and ratchet for locking said lever in position, said movable holding means being mounted for tripping said pawl upon releasing said jaw.
- 60 16. A device of the character described comprising, in combination, a pair of co-operating relatively slideable jaws, a pivoted lever for moving one of said jaws relative to the other jaw, movable means for releasably holding said movable jaw in position, and a pawl and ratchet for locking said lever in position, said movable holding means being mounted for tripping said pawl upon releasing said jaw.
- 65 17. A device of the character described comprising, in combination, a pair of co-operating relatively slideable jaws, a pivoted lever for moving one of said jaws relative to the other jaw, movable means for releasably holding said movable jaw in position, and a pawl and ratchet for locking said lever in position, said movable holding means being mounted for tripping said pawl upon releasing said jaw.

to the other, an intermediate member between said lever and said jaw, means for adjusting the position of said member relative to one of said last-mentioned parts, and
5 means independent of the lever for holding said intermediate member in adjusted position.

In testimony whereof I have hereunto signed my name in the presence of the two
subscribed witnesses.

JOSEPH EIFEL.
